UNITED STATES PATENT OFFICE.

JAMES H. RAND, OF NORTH TONAWANDA, NEW YORK.

INDEX.

1,418,467.

Specification of Letters Patent. Patented June 6, 1922.

Application filed October 3, 1919. Serial No. 328,125.

To all whom it may concern:

Be it known that I, JAMES H. RAND, a citizen of the United States, and resident of North Tonawanda, in the county of Niagara and State of New York, have invented new and useful Improvements in Indexes, of which the following is a specification.

This invention relates to indexes, and is a species of the genus more fully described and more broadly claimed in an application filed concurrently herewith.

In the accompanying drawings which illustrate the invention,

Fig. 1 is a front elevation of a part of an index containing the invention, parts being broken away;

Fig. 2 is a vertical section of the same;

Fig. 3 is an enlarged detail partly in horizontal cross section and partly in plan;

Fig. 4 is a cross section on an enlarged scale of one of the index slip holders on line 4—4 of Fig. 1;

Fig. 5 is a cross section on an enlarged scale of one of the index slip holders on line 5—5 of Fig. 1; and

Fig. 6 is a face view of a pair of the index slips.

The index frame may be of usual construction, and as herein shown consists of a back A, preferably of sheet metal, having its opposite side margins bent to form inwardly extending flanges a, a, providing channels for the ends of the sheaths or holders.

Each holder comprises a pair of relatively long and narrow, parallel, closed-faced sheaths, made of an integral piece of transparent, resilient, sheet material such as sheet celluloid. The opposite longitudinal margins of the sheet are folded over and inwardly upon the middle section 1, to form a pair of sheaths or compartments 2 and 3 arranged side by side, each folded margin terminating in a lip 4 to close the compartment.

Either side of the holder thus formed may be used as the front face, but I prefer to use the flat middle section 1 as the front face, as it affords a smoother and more nearly continuous surface when a number of holders are assembled in the frame, with fewer cracks for the accumulation of dust.

Furthermore each associated pair of index slips are more conspicuously grouped when marked by cracks only between pairs of slips than when a crack occurs between all adjacent slips as would be the case if surfaces 2 and 3 were presented at the front.

The front face of one compartment of each pair is cut out as shown at 5, to form an entrance opening through which the index slip may be inserted or removed, without removing the holder from the frame. In the preferred form, in which the middle section 1 is the front of the holder, this entrance opening 5 is cut through the middle section 1 opposite one of the folded margins 3.

The index slips 6 and 7 (Fig. 6), of paper or other suitable sheet material, are inserted or removed endwise into or from their respective compartments, the slip 6 bearing the name or other relatively permanent matter being placed in sheath 2, from which it cannot be removed without removing the holder from the frame, and the slip 7 bearing temporary or changing data being placed in sheath 3, in which it can be inserted or from which it can be removed through the opening 5 without disturbing the holder.

I claim:

1. A holder for index slips formed of an integral piece of transparent, resilient, sheet material, folded to form a pair of relatively long and narrow parallel compartments arranged side by side in the same plane, adapted to hold separate index slips.

2. A holder for index slips formed of an integral piece of transparent, resilient, sheet material, having its opposite margins folded over and inwardly upon the middle section to form a pair of relatively long and narrow parallel compartments arranged side by side in the same plane, adapted to hold separate index slips.

3. A holder for index slips formed of an integral piece of transparent, resilient, sheet material, folded to form a pair of relatively long and narrow parallel compartments arranged side by side in the same plane, adapted to hold separate index slips, the front face of one compartment being cut away near the end to form an entrance opening for an index slip.

4. A holder for index slips formed of an integral piece of transparent, resilient, sheet material, having its opposite margins folded over and inwardly upon the middle section to form a pair of relatively long and narrow parallel compartments arranged side by side in the same plane, adapted to hold

separate index slips, a part of the middle section opposite one of said folded margins, near its end, being cut away to form an entrance opening for an index slip. 10

Signed by me at North Tonawanda, N. Y., this 30th day of Sept., 1919.

JAMES H. RAND.
